UNITED STATES PATENT OFFICE.

FRANK E. FITZGERALD, OF WATERTOWN, NEW YORK.

TROUSERS-SUPPORT.

1,345,917.

Specification of Letters Patent.

Patented July 6, 1920.

Application filed July 24, 1919. Serial No. 313,051.

To all whom it may concern:

Be it known that I, FRANK E. FITZGERALD, a citizen of the United States, residing at Watertown, in the county of Jefferson and State of New York, have invented certain new and useful Improvements in Trouser-Supports, of which the following is a specification.

This invention relates to improvements in trouser supports, and has for its object to eliminate the usual belts which entirely encircle the body of the wearer, as well as the suspenders so commonly worn for supporting trousers. A further object is to provide a trousers support, which consists of a leather or other flexible strap which extends from the hip seam at one side across the back to the other hip seam leaving the front of the trousers clear and free, and thus obviating the necessity of buckling and unbuckling the belt in order to apply and remove the trousers. And a further object is to provide novel and simple means for adjusting the support and for effecting the proper tension for holding the trousers in place.

I attain these objects by the means set forth in the detailed description which follows, and illustrated by the accompanying drawing, in which—

Figure 1 is a top-plan view of a pair of trousers, to which my improved support is applied.

Fig. 2 is an enlarged broken right side elevation; showing the adjustable parts of the device.

Fig. 3 is an enlarged edge view of the combined buckle and key-ring support.

Fig. 4 is a top-plan view of the parts shown in Fig. 2.

In the drawing, 2 represents the top or waist-band of a pair of trousers, the front of which is split and overlapped in the usual manner at 3. 4 is the right hip seam, and 5 is the left hip seam, the said seams divide the trousers into front quarters or portions 6—6', and rear quarters or portions 7—7'.

My improved support consists of the following parts: 8 and 8' are similar right and left side loops or rings, preferably made out of metal, which are loosely supported by straps 9, the latter being bent upon themselves and detachably secured to the front portions 6—6', by snap-buttons 10, whose

shanks 10' pierce the straps 9 and the trouser band 2 in the usual manner, as best seen in Figs. 1 and 4. The loops 8 and 8' are preferably disposed an inch or two forwardly of the right and left hip seams 4 and 5. The support proper consists of two leather or other suitable flexible straps 11 and 12, preferably about the breadth and thickness of the ordinary belts. The strap 11 is preferably long enough to extend from the right to the left hip seams, and is held in place against the rear portion of the band 2 by loops 13, which are usually placed on all trousers. One end of the strap 11 is passed loosely through the ring 8', and then folded rearwardly between the band 2 and the body of the strap, and this end is detachably secured to the band 2 an inch or two rearwardly of the left hip seam 5, by a snap or other button 14. The opposite end of the strap 11 is fitted with a buckle 15, which is positioned near the right hip seam, the said buckle preferably having an integral depending spring hook 15' for supporting a key-ring (not shown) as best seen in Figs. 2 and 3. The strap 12 is relatively short and one end thereof is loosely passed through the ring 8 and is then bent rearwardly between the band 2 and the body of the strap, and is secured to the band 2 by a similar button 16. The opposite end portion of the strap 12 is perforated at frequent intervals to receive the tongue 15^a of the buckle, and by means of which the straps 11 and 12 are adjusted for properly holding the trousers in place. By the use of the snap buttons 10, 14 and 16 the support may be applied to or removed from a pair of trousers in a few minutes, and the disposition and arrangement of the support is such that substantially the entire front portions between the fasteners 10 are clear, and the trousers may be applied and removed at will without disturbing or requiring any handling of the support after it has been placed in position and adjusted. When my support is first applied to a pair of trousers, the wearer draws the short strap 12 through the buckle 15 until the band 2 is given the right tension to hold the trousers in place. The members 11 and 12 of the support always rest upon the hips, and when the strap 12 is drawn tight, owing to the loose connections between the strap 11 and the loop 8', and between the strap 12 and the loop 8', the strap 12 is drawn tight, owing to the loose connections between the strap 11 and the loop 8', and between the strap 12 and the loop 8'.

and the loop 8, the front and rear portions 6—6' and 7—7' are drawn toward the right and left hip seams 4 and 5, as indicated by the small arrows in Figs. 1 and 4. By this construction and arrangement of the support, the tension is distributed equally to all of the four quarters of the trousers, and there is no discomfort felt by the wearer. And furthermore, the band 2 of the trousers is drawn and held smoothly against the 10 waist of the wearer and does not wrinkle or buckle, as in the cases where the common belts are employed, because in the latter, the tension is entirely on the belt which sinks into the soft parts of the body, and correspondingly bulges the trousers above 15 and below the belts.

Trousers equipped with my improved support will hang evenly and gracefully, 20 and when properly adjusted require no handling or attention, unless the girth of the wearer changes.

Having thus described my invention, what I claim is—

In a support, the combination with a pair 25 of trousers having a band and having right and left hip seams, of rings detachably mounted on said band forwardly of said hip seams, a flexible strap having a buckle at one end disposed near the right hip seam, 30 the opposite end loosely engaging the ring at the left side and folded upon itself and secured to the trousers rearwardly of the left hip seam, a second strap loosely engaging the ring at the right side and folded upon it- 35 self and secured to the trousers rearwardly of the adjacent seam, the free end of the second strap being perforated and inserted through the buckle adapted to draw the four quarters of the trousers toward the 40 corresponding hip seams.

In testimony whereof I affix my signature.

FRANK E. FITZGERALD.
